Inventor,

UNITED STATES PATENT OFFICE.

EUGENE W. SCHNEIDER, OF NEW YORK, N. Y.; ELIZABETH CATHERINE SCHNEIDER EXECUTRIX OF SAID EUGENE W. SCHNEIDER, DECEASED.

SOUND-CONCENTRATOR FOR DEVICES FOR AIDING THE HEARING.

1,192,123.

Specification of Letters Patent.

Patented July 25, 1916.

Application filed October 15, 1915. Serial No. 55,941.

To all whom it may concern:

Be it known that I, EUGENE W. SCHNEIDER, a citizen of the United States, residing at Jamaica, in the county of Queens, city 5 and State of New York, have invented certain new and useful Improvements in Sound-Concentrators for Devices for Aiding the Hearing, of which the following is a full, clear, and exact description.

10 This invention relates to sound-collectors or "concentrators" for telephone instruments, particularly for the transmitters used in telephonic devices for aiding the hearing. Its object is to provide a concentrator 15 which is collapsed into small compass when not in use but which can be drawn out or extended whenever necessary or desirable.

To this and other ends, the invention consists in the novel features of construction 20 and combinations of elements hereinafter described.

One form of the invention is illustrated in the accompanying drawing, in which—

Figure 1 is a side view of the transmitter 25 and concentrator, with the latter extended for use; and Fig. 2 is a similar view but with the concentrator collapsed. Fig. 3 is a front view. Fig. 4 is a perspective view of one of the elements of the concentrator. 30 Fig. 5 is a detail sectional view, on a larger scale than the other views.

The transmitter casing shown at 10 is of circular form, having tubular sockets 11 at the bottom to serve as terminals to slip over 35 the pole-pieces of the battery (not shown). On the back, at the top, is an apertured metal plate 12 by which the device can be hung on the garment of the user, and a flexible conductor 13 connects the device 40 with the receiver or ear-piece, not shown.

The concentrator 14 is composed of a suitable member of concentric sliding rings or short cylinders 15, preferably of thin sheet metal such as spring brass, provided with 45 inner and outer shoulders 16, 17, to prevent the rings from coming apart, as will be readily understood. Preferably the rings are untapered. The innermost ring, which is also the smallest in diameter, is 50 riveted or otherwise secured around and to a central extension 18 of the sheet-metal cover 19, which latter is screw-threaded on the body of the transmitter casing 10 as clearly shown in Fig. 5. The extension 55 mentioned is preferably of the same depth

as the rings, so as to more effectively reinforce the latter and prevent them from being bent or distorted when in collapsed position. The outer edge of the outermost (and largest) ring is provided with a thick 60 bead 20 for convenient grasp in drawing out the concentrator and to take the pressure of the fingers in collapsing the device.

To hold the device in extended position and to prevent looseness, and consequent rattling of the rings, when the device is collapsed, the rings are provided with axially extending spring tongues 21, preferably cut from the ring itself and bent slightly outward, as shown more clearly in Figs. 4 and 65 70 5. The tongues are just short enough to permit the shoulders or beads 16 to snap in between the ends of the tongues and the beads 17. To facilitate collapse of the rings one into the other the free ends of the 75 tongues may be bent slightly inward and the coöperating beads rounded, as clearly indicated in Fig. 5. When the device is collapsed, with the rings nested one in the other, each tongue bears against the next 80 outer ring and thereby prevents looseness and rattling.

The concentrator is easily extended by a quick pull on the outer ring, grasped by the bead 14, and is collapsed with equal ease 85 by pressure of the fingers on the same part. It will of course be understood that with untapered rings the amount of "flare" or taper of the concentrator as a whole depends, other conditions being equal, upon 90 the number of rings used.

In Fig. 4, 22 represents the transmitter diaphragm, held by its edge on the transmitter casing 10 by the removable cap 19. The face of the cap-extension 18 is prefer- 95 ably concave, and is perforated as shown in Fig. 3.

It is to be understood that the invention is not limited to the construction herein specifically illustrated and described, but can 100 be embodied in other forms without departure from its spirit. It will also be clear that the device can be used on a receiver if desired.

I claim:

1. The combination with a telephonic transmitter, of a collapsible sound-concentrator on the face of the transmitter, comprising a plurality of sliding concentric rings or shells having inner and outer shoul- 110

ders to prevent separation of the rings when extended and provided with yielding devices adapted to bear laterally on the successive rings when the latter are nested or 5 collapsed one into the other.

2. A sound-concentrator for the purpose described, comprising a plurality of concentric sliding rings or shells adapted to nest or collapse one into the other, means to prevent 10 separation of the rings when extended, and yielding devices adapted to hold the rings in extended position and to bear laterally on the rings to prevent looseness thereof when nested or collapsed.
- 15 3. A sound-concentrator for the purpose described, comprising a plurality of concentric sliding rings or shells, having spring tongues adapted to bear laterally on the successive rings to prevent looseness thereof 20 when nested or collapsed.

4. A sound-concentrator for the purpose described, comprising a plurality of concentric sliding rings or shells, inner and outer shoulders on the edges of the rings to prevent 25 separation thereof when extended, and inwardly yielding spring tongues on the outside of the rings to coöperate with the inner shoulders and hold the rings in extended position and adapted to bear outwardly on the inner surfaces of the successive rings when the same are nested or collapsed.

- 30 5. The combination of a transmitter having a central extension, an inner ring or

shell fastened to the transmitter around the 35 said extension, and one or more sliding rings concentric with the inner ring, the said extension serving to reinforce or brace the rings against bending or distortion when they are nested or collapsed. 40

6. In combination with a telephone transmitter for aiding the hearing; of a central extension therefrom, said extension being adapted to be screwed over the exterior of the transmitter and to thereby clamp the 45 diaphragm thereto; the said extension having an annular portion coaxially alined and projecting outwardly from the transmitter, a ring engaged over said annular portion, said ring being supported and braced by said 50 annular portion, an outwardly projecting shoulder on said ring, a sound concentrator comprising a plurality of sliding concentric rings or shells, having inner and outer shoul- 55 ders to prevent separation of the rings when extended, one of said shoulders coöperating with the shoulder on the first mentioned ring, to secure the second mentioned rings to the first mentioned ring, yielding spring 60 tongues associated with the rings and adapted to hold the rings in extended position, said tongues being adapted to bear upon the periphery of the next outer rings and prevent the assemblage of rings from rattling when in collapsed position. 65

In testimony whereof I hereunto affix my signature.

EUGENE W. SCHNEIDER.
